UNITED STATES PATENT OFFICE.

SHORTRIDGE HARDESTY, OF LARCHMONT, NEW YORK, ASSIGNOR TO WADDELL & HARDESTY, OF NEW YORK, N. Y., A COPARTNERSHIP CONSISTING OF JOHN A. L. WADDELL AND MYSELF.

COUNTERWEIGHTING APPARATUS FOR LIFT BRIDGES AND THE LIKE.

Application filed February 17, 1927. Serial No. 163,861.

The invention provides certain improvements in the connections of the counterweights to the ropes by which they are carried, and is applicable to lift bridges and 5 various other structures which employ heavy weights suspended from a plurality of ropes. The accompanying drawings illustrate the invention in connection with a vertical lift bridge.

10 Fig. 1 is a side elevation of the connections at one end of a counterweight;

Fig. 2 is a face elevation of the same;

Fig. 3 is a plan of one of the guide blocks for the ropes;

15 Fig. 4 is an elevation of a portion of one of the blocks;

Fig. 5 is a section on the line 5—5 of Fig. 3;

20 Fig. 6 is a plan of one of the sheaves over which the ropes run, with a guide block below it;

Fig. 7 is a diagrammatic side elevation of the bridge omitting the operating gear.

The lift span 1 is carried between towers

25 2. From the ends of the span ropes 3 lead up over sheaves or pulleys 4 to counterweights 5. In Figs. 1 and 2 there is illustrated a single equalizing system. Ordinarily this is duplicated at each end of each 30 counterweight.

The counterweight 5 has an upwardly projecting portion 6 by which it is supported. The part 6 is pivotally connected directly to an equalizer bar 7 of structural steel; 35 which is pivotally connected at its upper corners to similar equalizer bars 8. These are pivotally connected at their upper corners through links 9 to similar equalizer bars 10 arranged in a transverse plane; and 40 the latter in turn to equalizer bars 11 to which are pivotally attached the rope sockets 12, which are connected to the ends of the several ropes 3. The arrangement is such that the sockets and rope ends are in 45 four compact rows of four ropes each; the four ropes in each row (Fig. 3) being equalized with each other through the bars 11 and 10 and the four rows (or equalizers 10) being equalized with each other 50 through the bars 8 and 7.

Above the equalizing system means are provided for holding the several ropes in fixed lateral relation with one another. A block 13 separates the ropes 3 as they run

downward from the sheave into two main 55 groups of eight ropes, one group on each side of the block, the centre line of the block being in line with the side of the sheave from which the ropes run down to the counterweight. From each side of the 60 block there is a group of four ropes which lead downward and inward as at 3^a, while the other four ropes from the same side of the block lead downward and outward as at 3^b. The tension on the ropes in the group 65 marked 3^a holds them close in against the block 13. The ropes 3^b which lead to the outer rows of sockets are retained in position against the block or spreader 13 by 70 means of plates 14 which are fastened by bolts 15. Each plate 14 has an eye-bolt 16 on the top by which it can be handled. The bolting of the plates 14 makes it easy to replace defective ropes as required, without the necessity of removal of the rope sockets. The rope grooves in the blocks 13 and 75 plates 14 may be straight if desired. But it is preferable to bring them in straight and parallel at the top as in Fig. 4 and to carry them out at the bottom in the directions of the sockets to which they are to be connected, and also to curve them in the other plane in the directions of the extreme leads of the ropes as shown in Fig. 5.

In Fig. 1 all the ropes 3, as illustrated in 80 full lines, converge upward. This is the position when the counterweight is up near the sheave over head. When the weights are down to the lowest position the angle of the ropes leading up from the block 13 85 is much less, being nearly parallel as indicated in dotted lines for the lowest position of the weight. Since the ropes are held in fixed lateral relation by the block, the upper portions thereof can vary their angular 90 positions without changing the position of the equalizer bars. This practically eliminates the usual noise and wear of the equalizer bars and pins as the weight rises and falls.

100 It will also be seen by referring to Fig. 1 that the maximum deflection of the ropes by the block 13 is comparatively slight and that each row of ropes is at some time during the motion of the counterweight subjected to practically no deflection, and passes between the block 13 and plates 14 in essentially a straight line. For these reasons the 105

proper functioning of the equalizer bars is not hindered by any material friction of the ropes with the block and plates.

The block 13 is held in position by means of struts 17 riveted at their upper ends to plates 18 on the ends of the block and at their lower ends to plates 19 fastened on the ends of the pin 20 by which the bracket 6 is pivotally connected to the lowest equalizer bar 7. The vertical components of the rope pressures on the guide are comparatively slight because of the slight maximum deflection of the ropes. The vertical components vary from a downward to an upward pressure as the counter weight falls. The ropes are capable of movement separately through the block 13 to allow the equalizers to function freely.

If desired, the blocks 13 can be made sufficiently wide to be retained in position by the inner rows of ropes, and to maintain contact at all times with the outer rows. Said outer rows would then be free to slide on the block, and the plates 14 and struts 17, or other connections, could be dispensed with. We prefer, however, to maintain the rigid connection to the counterweight or equalizer pins to locate the block and hold it securely in proper position.

Various modifications may be made by those skilled in the art without departing from the invention as defined in the following claims.

What I claim is:

1. A counterweighting apparatus for lift bridges and the like including in combination a weight, a sheave, ropes leading over said sheave, equalizers for distributing the pull of the weight to the several ropes and means between the equalizers and the sheave for holding the upper parts of the several ropes in two groups in adjacent planes parallel to the axis of the sheave, the ropes in each plane being in fixed lateral relation to one another.

2. A counterweighting apparatus for lift bridges and the like including in combination a weight, a sheave, ropes leading over said sheave, equalizers for distributing the pull of the weight to the several ropes and a guide block engaging the ropes between the sheave and the equalizers and holding

the lower portions at fixed angles with each other and holding the upper portions in two groups and permitting said groups to change 55 their angles as the weight rises and falls.

3. A counterweighting apparatus for lift bridges and the like including in combination a weight, a sheave, ropes leading over said sheave, equalizers for distributing the 60 pull of the weight to the several ropes and means between the equalizers and the sheave for holding the several ropes in fixed lateral relation to one another, said holding means including a fixed block engaged by said ropes 65 and detachable retaining members for holding the ropes in such engagement.

4. A counterweighting apparatus including in combination a weight, a sheave, ropes leading over said sheave, equalizers for distributing the pull of the weight to the several ropes, a guide block engaging the ropes between the sheave and the equalizers and separating them into groups converging from 70 the guide block toward the sheave and struts 75 for supporting the guide block from the weight.

5. A counterweighting apparatus including in combination a weight, a sheave, ropes leading over said sheave, equalizers for distributing the pull of the weight to the several ropes, a guide block engaging the ropes between the sheave and the equalizers and separating them into groups converging from 80 the guide block toward the sheave, said 85 guide block carrying the ropes in grooves which are curved at their upper ends in a direction to permit the upper portions of the ropes to converge at a varying angle.

6. A counterweighting apparatus including in combination a weight, a sheave, ropes leading over said sheave, equalizers for distributing the pull of the weight to the several ropes, a guide block engaging the ropes between the sheave and the equalizers and separating them into groups converging from 90 the guide block toward the sheave, some of said ropes (3^a) converging also from the block toward the equalizers so as to hold 95 the block in place between them.

In witness whereof, I have hereunto signed my name.

SHORTRIDGE HARDESTY.
